UNITED STATES PATENT OFFICE.

HENRY F. OSBORNE, OF NEWARK, NEW JERSEY, ASSIGNOR TO H. F. OSBORNE COMPANY, OF NEW JERSEY.

DESIGN FOR A RECEPTACLE MEMBER FOR MEAT OR OTHER PRESSES.

SPECIFICATION forming part of Design No. 35,079, dated September 10, 1901.

Application filed July 12, 1901. Serial No. 68,112. Term of patent 14 years.

To all whom it may concern:

Be it known that I, HENRY F. OSBORNE, a citizen of the United States, residing at Newark, in the county of Essex and State of New Jersey, have invented and produced a new and original Design for Receptacle Members of Meat or other Presses, of which the following is a specification, reference being had to the accompanying drawings, forming part thereof.

Figure 1 is a view in elevation of the receptacle member of a meat or other press, showing my design. Fig. 2 is a plan view of Fig. 1.

The leading feature of my design consists of the cup-shaped base portion having two upwardly-extending arms formed integrally with and rising from the edge and sides of same and meeting in a central bushing, substantially as shown in the drawings.

In the drawings, 1 designates the cup-shaped base portion having the spout 2 and provided with radially-disposed corrugations 3 on the bottom inside.

4 represents two arms formed integrally with and extending upwardly from the edge and side of the cup-shaped base portion, curving in the arc 5 toward each other, and meeting in the central bushing 6.

What I claim is—

The design for the receptacle member of a meat or other press, substantially as herein shown and described.

Signed at Newark, in the county of Essex and State of New Jersey, this 17th day of May, 1901.

HENRY F. OSBORNE.
